AUTOMATIC NEEDLE ASSEMBLING APPARATUS

Karlfried Lucke, 30 Schaefflerbachstrasse,
Augsburg, Germany

Filed July 30, 1957, Ser. No. 675,115

Claims priority, application Germany July 30, 1956

17 Claims. (Cl. 29—211)

The object of the invention is to provide a simple automatic apparatus which permits the rapid and correct setting and assembling of needles or pins for combs and the like in a satisfactory manner, i.e. without any faults. This apparatus is used for setting needles for the combs of comb segments of combing machines and top combs of such machines and can also be used for other parts of textile machines fitted with needles, for example needle strips, gill bars or needle rollers or needle bars for intersecting machine gill boxes, and also hacking machines.

The automatic needle setting and assembling apparatus according to the invention consists essentially of a needle chamber which serves to accommodate a plurality of needles, a periodically moved needle lifter, which at every movement grips a needle in the chamber and lifts it horizontally out of the said chamber, a tilting means which supports the needle at a point along its length in such manner that the needle tips over downwardly in a specific position, of an approximately vertical guide duct which tapers in the downward sense and in which the needle slides downwardly in the aforesaid specific position, and of a periodically moved conveying device whereby a needle strip which is to be filled and which is arranged horizontally below the guide duct is always advanced by the amount of the spacing of the needles.

The features of the invention will be described in more detail hereinafter with reference to examples of the invention illustrated in the drawings, wherein:

Figure 1 is a front elevation of an automatic needle setting apparatus, according to the present invention,

Figure 2 is a plan view thereof,

Figure 3 is a vertical sectional view taken on the line III—III of Figure 1, on a larger scale,

Figure 4 is a view taken in the direction A of Figure 3 on a smaller scale,

Figure 5 is a vertical sectional view taken on the line V—V of Figure 4 on the scale of Figure 3,

Figure 6 is a front elevation of the needle lifter,

Figure 7 is a vertical sectional view taken on the line VII—VII of Figure 2 through the needle supply container, on a larger scale,

Figure 8 is a vertical sectional view taken on the line VIII—VIII of Figure 7,

Figure 9 shows details of Figure 3 on a larger scale,

Figure 10 is a sectional view taken on the line X—X of Figure 9,

Figure 11 is a plan view of a needle strip,

Figure 12 is a cross sectional view of the needle strip taken on the line XII—XII of Figure 11,

Figure 13 is a view on a larger scale of parts of Figure 1.

Figure 14 is a sectional view in accordance with Figure 3 showing a simplified construction,

Figure 15 is a front elevation of a further embodiment of an automatic needle setting apparatus,

Figure 16 is a vertical sectional view on the line XVI—XVI of Figure 15.

In the drawings, 1 designates a box-like housing which

2

is closed at the front end by a plate 2 and in which the driving members are mounted.

Situated on the housing is a needle supply container 3, which is mounted on a carriage 4 which is mounted to be displaceable in the longitudinal direction B on the support pins 5 which are fixed on the housing. A shaking movement is imparted to this supply container in the direction B by means of a drive which is not shown in the drawings. Referring to Figure 7 the trough-shaped supply container 3 is provided centrally with a bottom aperture 6 and a channel 7 connected thereto. Provided in a housing 8 arranged centrally of the trough 3 is a slide 9 which covers the bottom aperture 6, and which is adjustable in the vertical sense by means of a screw 10 and which regulates the access of needles to the bottom aperture 6. For this purpose the underside of the slide is formed with two grooves 11 which extend in the longitudinal direction of the supply container 3 and through which, when the slide is adjusted appropriately, one needle at a time can slide, to fall into the channel 7 and be conveyed to a needle chamber 12 which has an oblique surface 13 (see Figure 14). Arranged at the lower end of the oblique surface 13 is an interchangeable plate-like needle lifter 14 which is moved vertically upwards and downwards and whose upper edge comprises an inclined surface 15 the length l of which (see Figure 6) corresponds to the length of a needle. The needle lifter has two arms 18 which bound the inclined surface 15. Also provided is a vertical guide wall 16 which bounds the needle chamber 12 and together with the inclined surface 15 of the needle lifter serves to support a needle 17 when the said needle lifter is moved upwards. Therefore, at the upward movement of the needle lifter 14, the needle 17 is lifted (see Figures 3 and 14) until it reaches the position 17a above a horizontal knife edge 19 of the guide wall 16, which is bounded on the other side by an inclined surface 20. A tilting means is provided which supports the needle in the horizontal position in such manner that the needle tips over downwardly in a specific position. In the simplified embodiment shown in Figure 14 there are provided for this purpose two pins 21, 22 which are arranged spaced from one another in such manner that according to Figure 14 the relatively thick shank end of the needle 17a is held between the inclined surface 20 and the pin 21, whereas the relatively thin needle point passes through between the inclined surface 20 and the other pin 22, i.e. the needle 17a swings round so that its point is lowermost and slides downwardly in an approximately vertical position 17b into a vertical guide duct 23. In the embodiment according to Figures 1 to 5 there is provided a driven roller 25 which is formed at its periphery with a longitudinal slot 24 for accommodating a needle, and which forms with the inclined surface 20 a channel 26 in which the needle 17a falls into the position 17c. Arranged at the opposite side of the roller at a slight adjustable distance therefrom are the two pointed pins 21, 22 which are directed approximately radially towards the roller. When the roller 25 rotates in the direction c the needle 17c falls into the slot 24 and is carried along by the roller. Then in the position of the roller illustrated in Figures 3, 9 and 10 the needle in the position 17d falls out of the slot 24 and into the position 17e in which it is supported at the shank end by the pin 21 whereas the needle point as shown in Figure 10 passes freely between roller 25 and pin 22 and accordingly the needle is tipped over downwardly in a vertical position with its point lowermost and falls downward in the position 17b shown in Figures 3 to 13. The pins 21, 22 are expediently constructed as screw pins in order that the spacing from the roller 25 can be adjusted accurately. The needle 17b is first of all guided by the two walls

27 and then falls into the upper guide duct 28 which tapers in the downward sense, and which merges into the needle guide duct 29. These needle guide ducts 28, 29 are formed in a slightly obliquely inclined plate 30 and are covered by a transparent plate 31 which is fixed in a readily removable manner. The plate 30 is connected fast to the front housing wall 2.

As shown in the drawings, more particularly Figures 3 to 5, the needle lifter 14 is connected to a slide 32 which is adapted to be moved upwards and downwards and which is mounted to be displaceable in the vertical sense on guide rods 33 of the plate 2, and is pressed downwardly by coil springs 34. The slide 32 is moved upwards and downwards by a drive which is not shown in the drawings. Also fixed on the slide 32 is a rack 35 which through the agency of a pinion 36 drives the roller 25.

As is shown in Figures 1, 2 and 13, a needle strip 37 which is provided with appropriate holes for accommodating needles is mounted so as to be displaceable in the longitudinal direction below the vertical needle duct 29. The needle strip rests in a guide rail 38 and is conveniently pressed against this guide rail by light clamping springs 39. Also provided is a conveying device which always advances the said needle strip by the amount of the needle spacing. Provided for this purpose is a horizontal slide 40 which is moved to and fro in the direction D and which always acts on the needle last inserted in the strip 37 and advances the strip by the amount of the needle spacing. According to Figures 1 and 2, the slide 40 which is mounted in a guide 41 is pressed by a spring 42 into its initial position. The sliding movement is effected by a reciprocated member 43 by way of an adjusting screw 44 by means of which the length of the advancing movement is adjustable.

According to Figures 11 and 12, the needle strip 37 consists of two metal clamping bars 45 and 46 which are connected by screws or the like and of an interposed wooden or plastic strip 47 which together with the clamping bar 45, which is grooved at its inner side, form holes 48 into which the needles 17 can be inserted, the said needles falling downwardly point foremost into these holes in the manner described hereinbefore from the needle duct 29.

By means of this needle strip 37 the needle shanks projecting freely as shown in Figure 12 can then be welded on to a comb or the like.

In place of the needle strip 37 it is also possible to arrange a needle bar, gill bar or the like of known construction below the needle duct 29. Then the needles are inserted with their points downwards immediately into the vertical holes of the said needle bar. The projecting needle shanks are then driven or pressed into the needle bar.

Figures 15 and 16 show a further form of embodiment of a needle fitting apparatus according to the invention. Here there is provided in the middle of the edge 19 a horizontal tilting edge 49 which is situated perpendicularly to the edge 19, and at which the needle lifted by a needle lifter 15 to the position 17a is then supported exactly centrally by the tilting edge 49. Since the centre of gravity of the needle is situated towards the left or right of the edge 49, the needle always tilts with its relatively heavy shank portion lowermost, into the position 17f and downwards into the tapering guide duct 51. The latter divides into the two guide ducts 52 which at 53 each comprise an arcuate recess acting as a stop, and at this region are so broadened that the falling needle at 17g impinges on the stop 53, tips over in the direction of the arrow E over the upwardly projecting edge 54 of the recess and is guided point downwards in the position 17d into the vertical needle duct 55.

In the embodiment shown in Figure 16 two needle lifters 50 and 56 are provided. Interposed between the needle chamber 12 and the guide wall 57 for the needle

lifter 50 is an intermediate chamber 58 which comprises an inclined surface 59. Provided between this intermediate chamber 58 and the needle chamber 12 is the needle lifter 56. This arrangement prevents any faults occurring during operation, i.e. it guarantees that only one needle will be brought each time into the tilted position 17a. The expression "needles" in the specification and claims is intended also to cover pins.

What I claim is:

1. In an assembling machine, a device for successively and automatically feeding elongated elements one end portion of each of which is heavier than the opposite end portion, such as pointed pins, needles and the like, in a downward direction with a predetermined one of said end portions of each element located at the bottom end thereof during downward movement thereof, in combination, positioning means for automatically and successively positioning single elements in a position for movement by gravity while the elements extend substantially horizontally, said positioning means including a movable supporting and moving means for supporting and moving single elements in a substantially horizontal position, and aligning means located with respect to said movable means for placing the end portions of successive elements in the same position; and a stationary tilting mechanism located in the path of movement of said elements for engaging each moving element at a portion intermediate said two end portions thereof, so that the heavier of said end portions turns downwardly about said tilting mechanism, whereby a selected end portion of each element is located in a downwardly pointing position.
2. In a device as recited in claim 1, said tilting means acting on said elements to locate the thinner ends thereof in a downwardly directed position.
3. In a device as recited in claim 1, said tilting means including an elongated surface portion against which each element is located in a horizontal position for free falling movement therefrom, and a pair of stationary pins directed toward and terminating short of said elongated surface portion, said pins respectively having free ends in a horizontal plane in which each element is located when it engages said surface portion and said free ends of said pins being substantially equidistantly spaced from said surface portion by a distance less than the thickness of the thicker end of each element and greater than the thickness of the thinner end of each element plus the distance of the thinner end of each element from said surface portion, and said pins being spaced from each other by a distance slightly less than the length of each element and being positioned respectively in alignment with the end portions of each element when it engages said surface portion, whereby irrespective of which of said pins is engaged by the thicker end of each element, each element will turn in a direction which places its thinner end in a downwardly directed position before moving downwardly beyond said pins.
4. In a device as recited in claim 3, said surface portion forming part of an inclined surface which is inclined with respect to horizontal and vertical planes.
5. In a device as recited in claim 3, said surface portion forming part of a curved surface.
6. In a device as recited in claim 3, said surface portion forming part of a cylinder and being in the form of an axially extending groove formed in the exterior surface of said cylinder.
7. In a device as recited in claim 6, said cylinder being turnable about its axis for advancing an element in said groove thereof to a position where each element would fall freely from said groove were it not for the action of said pins.
8. In a device as recited in claim 1, said tilting means being a single member for engaging said point and acting on said elements to locate the thicker ends thereof in a downwardly directed position.
9. In a device as recited in claim 8, said tilting means

being in the form of a stationary member having a relatively thin straight top edge extending substantially horizontally in a direction perpendicular to each element when it is horizontally positioned for free falling movement and said top edge being located substantially midway between the ends of each element, so that when said elements successively engage said edge the thicker and consequently heavier end of each element compels the latter to turn around said edge with the thicker end of each element directed downwardly before each element moves downwardly beyond said edge.

10. In a device as recited in claim 9, second tilting means located underneath said first-mentioned tilting means laterally of said top edge and in the path of downward movement of said elements when they fall freely downwardly beyond said edge to engage and interrupt the movement of the thicker end of each element while freeing each element for free turning movement about the thicker end thereof to approximately a position where the thinner end of each element is directed downwardly while the thicker end thereof is engaged by said second tilting means so that the position of each element is automatically reversed by said second tilting means.

11. In a device as recited in claim 1, adjusting means operatively connected with said tilting means for adjusting the latter to cooperate with elements of different thickness.

12. In a device as recited in claim 1, said positioning means including a first stationary member having a downwardly inclined surface down which the elements are adapted to roll one after the other while in a substantially horizontal position, a second stationary member having a flat vertical surface spaced from, directed toward, and extending from an elevation higher than to an elevation lower than the bottom end of said inclined surface, said first member having a flat vertical surface extending downwardly from the bottom end of said inclined surface thereof parallel to and spaced from the flat surface of said second member so that said flat surfaces defined between themselves a vertical guideway, said second member having a top horizontal edge at the top end of said flat surface thereof and said second member having a downwardly inclined surface extending downwardly from said top end thereof and inclined in the same direction as said inclined surface of said first member, and a lifting plate located in said guideway in slidable engagement said flat surfaces for vertical reciprocating movement and having an upwardly directed face inclined in the same sense as said inclined surfaces; and means for reciprocating said plate in a stroke which locates said face thereof below the bottom end of said inclined surface of said first member at the bottom of said stroke and in a position high enough to at least form an extension of the inclined surface of said second member at the top of said stroke so that elements on the inclined surface of said first member will be separately and successively raised during successive strokes of said plate to the top end of the inclined surface of said second member to be positioned for free falling movement downwardly along the inclined surface of said second member while each element is horizontal.

13. In a device as recited in claim 1, said tilting means being located adjacent said movable means substantially at the top of the path of free falling movement of the elements to engage the latter substantially at the instant when said movable means positions the elements in said position for free falling movement.

14. In an assembling machine, a device for arranging elongated elements one end of which is thicker than the other in a predetermined relation with respect to each other, in combination, positioning means for automatically and successively positioning single elements in a position for free falling movement by gravity while the elements extend horizontally, said positioning means including a movable means for supporting and moving single elements in a horizontal position, and aligning means lo-

cated with respect to said movable means to place the ends of successive elements in the same position on said movable means; and stationary tilting means located in the region of said movable means and in the path of free falling movement of the elements for engaging a single point intermediate two portions of a falling element so that the heavier portion of said portions turns downwardly about said tilting means whereby a selected end of each element is located in a downwardly pointing position; a receiving means positioned beneath said tilting means in the path of downward movement of the elements from said tilting means, said receiving means being formed with a row of receiving openings having open top ends into which the elements are adapted to successively move with said predetermined ends thereof first entering said openings; and a shifting means operatively connected with said receiving means for shifting the latter step by step in the direction of said row to locate said openings successively in the path of movement of the elements to 20 successively receive the latter whereby said elements will become automatically respectively located and assembled in said openings with said predetermined ends of said elements forming the bottom ends of the latter.

15. In an assembling machine, a device for automatically arranging and assembling elongated elements, one end of which is thicker than the opposite end, in a position in which a selected end is located below the other end of each element, in combination, a support having a downwardly inclined face and a pair of spaced aligning means spaced in horizontal direction of said inclined face a distance corresponding to the length of said elements; means for supplying said elements to said inclined face to form a row between said aligning means; a plate having a downwardly inclined top portion located at the lower end 35 of said face and being reciprocable in upward and downward directions and passing the lower end of said face during its stroke to successively carry single elements on said top portion to a higher position; another support adjacent said plate having a downwardly inclined face with a horizontal top edge located in the region of said higher position so that single elements on said top portion move downwardly on said inclined face of said support; and tilting means including a pair of stationary pins having ends spaced from each other in direction of said top edge 40 and being equidistant from said top edge, said pins being located slightly inwardly of said aligning means so that each pin engages a point of a downwardly moving element on the thicker end of the same while the other end of the element passes the other pin whereby the element tilts about the pin engaging the thicker end so that the thinner end of the falling element leads in downward direction.

16. In an assembling machine, a device for automatically arranging and assembling elongated elements, one end of which is thicker than the opposite end, in a position in which a selected end is located below the other end of each element, in combination, a support having a downwardly inclined face and a pair of spaced aligning means spaced in horizontal direction of said inclined face a distance corresponding to the length of said elements; means for supplying said elements to said inclined face to form a row between said aligning means; a plate having a downwardly inclined top portion located at the lower end of said face and being reciprocable in upward and downward directions and passing the lower end of said face during its stroke to successively carry single elements on said top portion to a higher position; another support adjacent said plate having a downwardly inclined face with a horizontal top edge located in the region of said higher position so that single elements on said top portion move downwardly on said inclined face of said support; a cylinder turnable about a horizontal axis and having at least one axial groove in the surface thereof, the cylinder being located at the lower end of said inclined face of said support so that during turning movement of

said cylinder single elements are positioned in said groove and are carried by said cylinder to a position in which they drop out of said groove; tilting means including a pair of stationary pins having ends located slightly inwardly of the ends of said groove and spaced from each other in direction of said groove, said ends being equidistant from the surface of said cylinder so that each pin engages a point of a downwardly moving element on the thicker end of the same while the other end of the element passes the other pin whereby the element tilts about the pin engaging the thicker end so that the thinner end of the falling element leads in downward direction; means for turning said cylinder; and means for reciprocating said plate.

17. A device as set forth in claim 16 and including means connecting said means for turning said cylinder and said means for reciprocating said plate for synchronous operation.
